UNITED STATES PATENT OFFICE.

ROBERT WARG, OF MILWAUKEE, WISCONSIN.

STEAM-RADIATOR.

No. 916,641.

Specification of Letters Patent. Patented March 30, 1909.

Application filed March 23, 1908. Serial No. 422,759.

To all whom it may concern:

Be it known that I, ROBERT WARG, a citizen of the United States, and resident of Milwaukee, in the county of Milwaukee and State of Wisconsin, have invented certain new and useful Improvements in Steam-Radiators; and I do hereby declare that the following is a full, clear, and exact description thereof.

10 The object of my invention is to provide a simple, economical and effective steam-radiator, the construction and arrangement of the radiator-base being such that a continuous and direct flow of steam is passed 15 through the radiator, thereby overcoming the liability of air-pockets being formed therein, and also rendering it possible to dispense with steam-pressure in order to maintain a uniform heating surface throughout the radiating coils.

15 The invention consists in various details of construction and combination of parts as will be hereinafter fully set forth with reference to the accompanying drawings and subsequently claimed.

20 In the drawings: Figure 1 represents a sectional plan view of a radiator embodying the features of my invention, with parts broken away to better illustrate the details, 25 and Fig. 2, a sectional elevation of same, as indicated by line 2—2 of Fig. 1, with a portion of the steam-coil in full.

25 Referring by numerals to the drawings, 1, 1, indicate hollow radiator bases, each being provided with a longitudinal central partition 2, which partition divides the base into separate chambers 3, 4, respectively. The chambers are connected by series of 30 looped steam-pipes 5, in screw-thread connection with apertures in the upper wall 6 of the base, the apertures being upon opposite sides of the partition.

35 One end of each base is provided with a transverse steam-head 7 having steam-inlet and discharge openings 8, 9, in its ends and upon opposite sides of the partition, the 40 openings being faced at their outside edges for the reception of suitable packing. The bottoms of the radiator-bases are inclined in 45 the direction of their heads, whereby condensation is caught therein and drained from said heads by suitable drip-pipes 10 tapped into the former.

50 In practice, two or more of the above described radiator sections are coupled together with their abutting openings 8, 9,

aligned, and between the faced edges of the openings are placed metallic rings 11, which rings serve to pack the joints thus formed. These rings are also placed upon the first 60 and last radiator base openings, there being threaded apertured caps placed over said rings for the reception of steam inlet and discharge pipes, not shown. The caps are provided with openings into which are fitted 65 headed tie-rods 12, which rods, by means of nuts 13 in threaded - connection therewith, serve to draw the sections or bases together and maintain them in position.

70 From the foregoing it will be seen that exhaust may be utilized direct from an engine without causing back - pressure, the steam passing through the entire radiator and carrying air ahead of it, said steam being finally discharged to atmosphere. By 75 this arrangement of steam circulation air-pockets caused through condensation of steam are entirely eliminated from the coils, it being understood that live-steam may be utilized with similar results, in which case 80 the pressure would be nominal, owing to the fact that an uninterrupted flow of steam is maintained. When live-steam is used in a system employing radiators of my construction, any well known method of connection from the last radiator may be 85 employed. Where it is desired to carry steam-pressure in the system, the last radiator is provided with a closed discharge-end, and a suitable air vent valve in order to dispel 90 air from said system.

I claim:

1. A steam-radiator comprising a longitudinal hollow base, a longitudinal centrally disposed partition extending from end to 95 end of the base, whereby separate chambers are formed, a transverse steam-head at one end of the base having oppositely disposed steam-inlet and discharge openings therein upon opposite sides of the longitudinal partition, and transverse looped steam-pipes in connection with the hollow base upon opposite sides of the partition.

100 2. A steam-radiator having a plurality of parallel sections, each of which sections comprises a longitudinal hollow base having a longitudinal centrally disposed partition-wall extending from end to end thereof, whereby separate chambers are formed, each hollow base being formed with a transverse 105 steam-head at one end having steam-inlet and discharge openings upon opposite sides

2
of its partition in direct communication with the steam-head of the adjacent hollow base, and a series of looped pipes for each section, each series being connected to a section upon opposite sides of its partition-wall.

In testimony that I claim the foregoing I

have hereunto set my hand at Milwaukee, in the county of Milwaukee and State of Wisconsin in the presence of two witnesses.

ROBERT WARG.
